DESIGN FOR A FORK AND SPOON.

Design No. 12,554, dated November 1, 1881.

UNITED STATES PATENT OFFICE.

HIRAM W. HAYDEN, OF WATERBURY, CONNECTICUT, ASSIGNOR TO HOLMES,
BOOTH & HAYDENS, OF SAME PLACE.

DESIGN FOR A FORK AND SPOON.

SPECIFICATION forming part of Design No. 12,554, dated November 1, 1881.

Application filed September 19, 1881. Term of patent 14 years.

To all whom it may concern:

Be it known that I, HIRAM W. HAYDEN, of Waterbury, county of New Haven, in the State of Connecticut, have invented or produced a new and ornamental Design for the Handles of Spoons and Forks, and the following is declared to be a description of the same.

This design relates to both the back and front of the handle of a fork or spoon; and it consists of raised bands, beads, figures, and ornaments upon a smooth polished background, and the said design is known as the "Bismarck" pattern.

Upon both front and back of the fork or spoon handle there is a bead, *a*, which runs the entire length of the handle on both sides, except where the ornaments *b* and *c* intersect it, as shown in the accompanying photograph views. At the extreme end of the handle of the fork or spoon there is an ornamental design representing a portion of the sun with diverging rays, as shown at *d*, and the lines composing said rays are divided by two segmental beads and a segmental row of dots, as shown at *e*, and at the ends there are segmental beads and leaflet ornaments at *f*. The beads *g* *g'* pass diagonally across the surface of the handle and divide it, as shown, into three panels, *h*, *i*, and *k*. In the panel *h* is a rose-branch with leaves and flowers in relief, and in the panel *k* is a stem with three-part leaves and berries; but the panel *i* is plain or without ornament.

The ornamental portion at *b* is alike on both sides of the handle, and consists of transverse curved bands or beads with intervening leaflet ornaments, the middle range of ornaments being a spray of leaves and berries, as shown. The ornamental portion at *c* is alike on both sides of the handle, and consists of two cross-beads with intersecting diagonal beads and central dots between them. The back of the fork or spoon at *l* may be plain and polished.

I claim as my invention—

1. The design of the shape and configuration of the ornamental end portions, *d*, *e*, and *f*, of the handle, as shown and described.

2. The design of the shape and configuration of the diagonal beads *g* *g'*, the rose ornaments in the panel *h*, and the leaf and berry ornament in the panel *k*, as shown and described.

3. The design of the shape and configuration of the beads *a* and ornament *b* upon the handle, as shown and described.

4. The design of the shape and configuration of the fork or spoon handle, consisting of the raised ornaments *d*, *e*, and *f*, beads *g* *g'*, rose *h*, leaflet ornaments *k*, and bands *b* *c*, substantially as shown and described.

Signed by me this 15th day of September, A. D. 1881.

H. W. HAYDEN.

Witnesses:

GEO. H. BENHAM,
F. M. BRONSON.
